Term of patent 14 years

(Cl. D64—11)

FIG. 1.

FIG. 2.

Fig. 1 is a front elevation of a calculator console unit, embodying our design.

Fig. 2 is an elevation thereof as seen from the left side of Fig. 1.

The right side of the unit is the same as the left side and the rear of the unit is plain. The dominant features of our design reside in those portions shown in full lines on the drawing.

We claim:

The ornamental design for a calculator console unit, as shown and described.
